UNITED STATES PATENT OFFICE.

ROBERT J. McBRIEN, OF EASTLAND, TEXAS.

COOKER.

1,420,562.

Specification of Letters Patent. Patented June 20, 1922.

Application filed November 13, 1920. Serial No. 423,861.

To all whom it may concern:

Be it known that I, ROBERT J. McBRIEN, a citizen of the United States, residing at Eastland, in the county of Eastland and 5 State of Texas, have invented new and useful Improvements in Cookers, of which the following is a specification.

This invention relates to cooking vessels, and has for its primary object the provision 10 of a vessel designed for association with the exhaust pipe of a motor operated vehicle so that the heat from the exhaust of the motor may be utilized to cook the food arranged within the vessel, thus making it 15 possible for the occupants of the vehicle to have a hot meal at a nominal cost.

The nature and advantages of the invention will be better understood when the following detail description is read in connection 20 with the accompanying drawings which form part of this application.

In the drawings like numerals of reference indicate the similar parts in the several views and wherein:—

25 Figure 1 is a fragmentary view of a motor operated vehicle showing the position of the cooking vessel thereon.

Figure 2 is a perspective view of the cooking vessel.

30 Figure 3 is a transverse sectional view taken on line 3—3 of Figure 1.

Figure 4 is a detail view of the inner cover.

Figure 5 is a similar view of the outer 35 cover.

Referring to the drawings in detail A indicates generally a motor operated vehicle, beneath the floor board B of which is arranged the exhaust pipe C.

40 The device forming the subject matter of my invention comprises a vessel 10 constructed from any suitable material preferably aluminum. This vessel 10 may also vary in size and configuration without departing from the spirit of the invention, while removably arranged within the vessel is a tray 11. There is also an inner cover 13 having centrally disposed knob 14, and an outer cover 15. The outer cover is lined with 45 asbestos and provided with flanges to fit snugly about the sides of the vessel 10, these flanges being indicated at 16. The outer cover is also provided with a hollow knob 17 which receives the knob 14 of the inner 50 cover, so that both of the covers can be removed from the vessel, or associated there-

with when desired. The asbestos lined cover is utilized to prevent the heat and odor from escaping from the vessel 10 into the vehicle. The bottom of the vessel 10 60 is formed with a longitudinally disposed groove 18 to receive the exhaust pipe C upon which the cooking vessel is supported.

As shown in Figure 1 the vessel 10 is arranged beneath the floor board B of the vehicle at a point between the front seat and the motor. The groove 18 is arranged to one side of the longitudinal center of the vessel shown in Figure 1 without contacting the frame of the vehicle. In this position 70 the cooking vessel is entirely out of view, and it can be readily removed from beneath the floor board when desired. For the purpose of holding the covers on the vessel as well as holding the latter in proper position 75 upon the exhaust pipe, I make use of a plurality of substantially U-shaped clamping elements 20 and 21 respectively, these elements being connected together by a transverse rod or the like 22. The clamping elements embrace the vessel 10 and have their terminals detachably connected with the covers, that portion of the clamping elements extending across the bottom of the vessel passing under the exhaust pipe C as 80 indicated at 23. Manifestly, I have devised a cooking vessel wherein the food stuff may be arranged at the beginning of a trip, utilizing the exhaust from the engine of the vehicle to cook the food, so that the occupants of the car may at the proper time 85 have the benefit of a hot meal at a nominal cost, and at the same time eliminate the necessity of carrying lunches which occupy considerable space in the car. 90

95 While it is believed that from the foregoing description the nature and advantages of the invention will be readily apparent, I desire to have it understood that I do not limit myself to what is herein shown 100 and described, and that such changes may be resorted to as fall within the scope of what is claimed.

What I claim is:—

1. A device of the class described comprising a vessel having a longitudinally disposed groove in the bottom thereof to receive the exhaust pipe of a motor operated vehicle, a partition dividing the receptacle into compartments, a handle carried by said 110 partition, an inner cover having flanges adapted to engage the walls of the vessel at

the inner side thereof, a knob arranged centrally of said cover, an outer cover including flanges adapted to engage the outer sides of said walls of the vessel, a hollow knob 5 carried by the outer cover and adapted to receive the knob of the inner cover, a lining of asbestos arranged between the respective covers, and means for holding both the receptacle and said pipe and also holding the cover in its place on the receptacle.

2. A device of the character described comprising a receptacle having a longitudinal groove in the bottom thereof adapted to receive the exhaust pipe of a motor operated vehicle, a cover for the receptacle, bifurcated lugs carried by said cover, a pair of substantially U-shaped clamping members

extending across the bottom of said pipe and having their limbs arranged at the opposed sides of the receptacle, said limbs being pivoted to the portion of the clamps extended across the bottom of the receptacle and received by said bifurcated lugs, adjusting nuts associated with said limb whereby said clamps hold the receptacle 25 upon the pipe and the cover in position upon the receptacle, and a reinforcing member connecting the corresponding limbs of the respective clamps at each side of the receptacle. 30

In testimony whereof I affix my signature.

ROBERT J. McBRIEN.
